UNITED STATES PATENT OFFICE.

JOHN SCHMIDT, OF ST. LOUIS, MISSOURI, ASSIGNOR TO INTERNATIONAL VENDING MACHINE COMPANY, OF ST. LOUIS, MISSOURI, A CORPORATION OF MISSOURI.

VENDING-MACHINE.

No. 909,687.

Specification of Letters Patent.

Patented Jan. 12, 1909.

Application filed August 5, 1907. Serial No. 387,008.

To all whom it may concern:

Be it known that I, JOHN SCHMIDT, a citizen of the United States, and a resident of the city of St. Louis and State of Missouri, have invented a new and useful Improvement in Vending-Machines, of which the following is a specification.

This invention relates to machines for vending cigars and has for its principal objects to insure the proper delivery of the cigars without injury thereto, to expose the use of slugs, and to attain other advantages hereinafter set forth.

The invention consists in the parts and in the arrangements and combinations of parts hereinafter described and claimed.

In the accompanying drawing, which forms part of this specification, and wherein like symbols refer to like parts wherever they occur, Figure 1 is a vertical cross-section of a cigar vending machine embodying my invention; Fig. 2 is a perspective view of the hopper and delivery cylinder; Fig. 3 is an end view of the delivery cylinder; Fig. 4 is a longitudinal sectional view of the delivery cylinder on the line 4—4 of Fig. 3; Fig. 5 is a longitudinal sectional view of the delivery cylinder on the line 5—5 of Fig. 3; Fig. 6 is a detail view of the cylinder centering device; Fig. 7 is a side view of the machine at the beginning of the actuating movement; Fig. 8 is a similar view showing the positions of the parts at the beginning of the return movement; Fig. 9 is a perspective view of the coin hopper; Fig. 10 is a vertical section thereof; and, Fig. 11 is a detail view of the counterweighted bottom of the coin hopper.

My vending machine comprises a casing or housing 1 inside of which are mounted the feeding and delivery mechanisms and the main portions of the actuating mechanism. The main frame upon which these parts are mounted comprises a base portion 3 and two sides 4, preferably made of a single plate of heavy sheet metal. The several shafts hereinafter mentioned are journaled in the said side portions of the frame.

The delivery mechanism comprises a low cylindrical shell 5 fixed to a shaft 6 which is journaled in the side plates. This cylindrical shell is preferably made of sheet metal and has longitudinal depressions or pockets 7 formed in the periphery thereof of

sufficient size to accommodate a cigar or such other article as it may be desired to deliver. Each of the depressions or pockets has a false bottom 8 therein, and between the bottom of the pocket and the false bottom is a spring 9 which normally holds the false bottom in its outermost position. The spring is preferably a strip or plate of resilient metal bent into an arc whose ends bear against the bottom of the pocket near the ends thereof. The false bottom and the spring are held in place by a screw bolt 10 or other suitable fastener which extends through them and the bottom of the pocket and is provided with a nut or enlargement inside of the cylinder. The hole in the false bottom is countersunk by depressing the edges thereof, whereby the beveled head of the screw bolt lies flush with the upper surface of said false bottom, and the spring plate is positioned by the downwardly projecting margin of said hole. Above said delivery cylinder is the feed mechanism. This feed mechanism comprises a hopper of which the side plates 4 of the frame constitute the ends. The sides of the hopper consist of movable members, preferably endless belts 11, 12 of rubber or other elastic material. These movable sides are arranged at a considerable angle to each other, one of them 11 being nearly horizontal and the other 12 being nearly vertical. The frame is provided with a support 13 for an ordinary cigar box in such position that the lower end of the box overlaps the outer end of the horizontal side of the hopper. The endless belts constituting the movable sides of the hopper are mounted upon the drums or shafts 14, 15, which are provided with sprocket wheels 16, 17. Over these sprocket wheels passes a sprocket chain 18 which cooperates with idle sprocket wheels 19 and is arranged to be actuated as hereinafter described. The hopper opening or space between the movable members of the hopper is immediately above the delivery cylinder, and the cylinder actuating mechanism is arranged to bring the pockets therein into register with said opening successively. By this arrangement, the lowermost cigar or other article in the hopper is delivered into the pocket, and the yielding false bottom of the pocket protects the cigar against injury during the movement of the cylinder. A roller 20 is mounted in the frame and has a

gear wheel 21 meshing with a gear wheel 22 fixed to the shaft of the sprocket wheel 17.

In order to prevent the hopper from becoming clogged, the movable sides are arranged to be moved simultaneously, the horizontal side being moved towards the hopper opening at the same time that the vertical member is moved upwardly therefrom. This upward movement of the vertical member has a tendency to straighten out the cigars and to relieve the lowermost cigars from the weight of those above them. This movement of the horizontal side towards the delivery opening occurs during the forward stroke of the actuating mechanism; and the return stroke of the actuating mechanism causes a reversal of the movement of the movable sides of the hopper. By this arrangement, the forward movement of the delivery cylinder brings an empty pocket into register with the opening of the feed hopper so that the lowermost cigar therein is free to drop into said pocket. As hereinafter described, the delivery cylinder is provided with a snap-acting centering device so arranged that the pocket of the delivery cylinder registers with the hopper opening before the end of the forward movement of the horizontal side of the hopper. In consequence of this arrangement, the movement of the horizontal side has a tendency to dislodge and feed forwardly the bottommost cigar in case it should become stuck.

The actuating mechanism comprises a manually-operable push-bar 23 which traverses the end of a coin chute 24. This coin chute terminates in a constricted portion 25 which constitutes a trap or seat for a coin. A coin 26 of proper size resting in this seat is in position to bear against the end of a lever 27 to which is fastened one end of a link 28 whose other end is connected to a pawl 29 arranged to engage the tooth of a ratchet wheel 30 mounted on the shaft of a delivery cylinder. The manually-operable bar has a tooth or projection 31 thereon arranged to bear against the lowermost tooth of a ratchet wheel 32 fixed on the shaft of the delivery cylinder. The cylinder is also provided with a snap-acting centering device of suitable type. As illustrated in the drawing, this centering device comprises a star wheel 33 mounted on the shaft of the delivery cylinder, and an anti-friction roller 34 mounted upon a spring-pressed arm 35 arranged to bear against the periphery of said star wheel. By this arrangement, the pressure of the spring transmitted through the anti-friction roller and the star wheel causes a rapid movement of the cylinder as soon as the roller passes the apex of the tooth of the star wheel and before the actuating bar reaches the inner limit of its movement. The actuating bar carries a pin 36 which rests in an elongated slot or yoke of a lever or pivoted arm 37, which is held in normal position by a spring 38. This arm is fixed to the sprocket chain 18 which passes over the sprocket wheels mounted on the belt-actuating shafts and also over the idle sprockets, whereby both the forward and the backward movement of the actuating bar are transmitted to the belts. The inward movement bears the actuating bar against the coin, which constitutes an element in the train for disengaging or unlocking the cylinder to permit rotation thereof. When the coin has performed its function in this train, it is ejected into a chute 40 which terminates in a slot 41 in the side of a coin box 42. The coin trap or rest has a constricted channel or passageway 43 beneath it leading into this chute 40, said passageway being intended to eliminate coins of small size. The top or side of the coin box is provided with a glass panel 44 to permit the inspection of the contents. The bottom 45 of the coin box is a plate pivotally mounted near one end and heavily weighted at the shorter end. The weight of the short end is sufficient to sustain a number of coins resting on the bottom plate, but is small enough to be overbalanced by a considerable number of coins. By this arrangement, the contents of the coin box remain in full view until there is a considerable number of coins. In fact, the counterweight is not uniformly overbalanced by the weight of a definite number of coins, because the leverage action varies with their positions. The liability to detection thus brought about has a tendency to protect the machine against the use of slugs and the like. Beneath the dumping bottom of the coin box is a chute which opens into a suitable chamber or receptacle in the interior of the casing.

Obviously, my device is capable of considerable modification within the scope of my invention, and therefore, I do not wish to be restricted to the particular construction shown and described.

What I claim as my invention and desire to secure by Letters Patent is:

1. A vending machine comprising a hopper which is composed of two end plates and two reciprocatable belts between said plates, one of said belts being nearly horizontal and the other being nearly vertical, and means for moving said belts simultaneously.
2. A vending machine having a feed hopper composed of two end plates and two reciprocatable belts, one of said belts being nearly horizontal and the other being nearly vertical, and means for reciprocating said belts.
3. A vending machine having a delivery mechanism, a nearly horizontal belt forming one side of a feed hopper therefor and a nearly vertical belt forming another side thereof, and means for moving said horizontal belt.

- tal side towards the delivery mechanism and simultaneously moving said vertical side away from said delivery mechanism and vice versa.
5. A vending machine comprising actuating mechanism, a delivery device and a hopper for feeding said delivery device, said hopper comprising a nearly horizontal belt forming one side thereof and a nearly vertical belt forming another side thereof, means for moving said horizontal side towards the delivery mechanism during the forward stroke of the actuating mechanism and simultaneously moving said vertical side away from said delivery mechanism.
10. A vending machine comprising actuating mechanism, a delivery device, and a hopper, said hopper comprising two elastic sides, and means for reciprocating said sides in opposite directions simultaneously.
15. A vending machine comprising a delivery cylinder having peripheral pockets and a hopper above said cylinder, said hopper having two movable sides, means for moving one of said sides towards the hopper opening and means for actuating said cylinder comprising a snap acting device arranged to center the pockets below said hopper during the movement of said side towards the hopper.
20. 6. A vending machine comprising a delivery cylinder having peripheral pockets and a hopper above said cylinder, said hopper having two movable sides, means for moving one of said sides towards the hopper opening and means for actuating said cylinder comprising a snap acting device arranged to center the pockets below said hopper during the movement of the horizontal side towards the hopper opening.
25. 7. A vending machine comprising a delivery cylinder having peripheral pockets, and a hopper above said cylinder, said hopper

having a substantially horizontal side and a substantially vertical side, and means for moving the horizontal side towards the hopper opening and simultaneously moving the vertical side away from said hopper opening, and means for actuating said cylinder comprising a snap-acting device arranged to center the pockets below said hopper during the movement of the horizontal side towards the hopper opening.

8. A vending machine comprising a delivery cylinder having peripheral pockets, and a hopper above said cylinder, said hopper having a substantially horizontal side and a substantially vertical side, and means for moving the horizontal side towards the hopper opening and simultaneously moving the vertical side away from said hopper opening, said means being adapted to reverse the movement of said sides, and means for actuating said cylinder comprising a snap-acting device arranged to center the pockets below said hopper during the movement of the horizontal side towards the hopper opening.

In testimony whereof I have signed my name to this specification in the presence of two subscribing witnesses this 2nd day of August, 1907.

JOHN SCHMIDT.
